By A. T. Harboe, Attorney.

UNITED STATES PATENT OFFICE.

FRANK H. FISSE, OF CINCINNATI, OHIO, ASSIGNOR TO THE K-W AUTO SPECIALTY COMPANY, OF CINCINNATI, OHIO, A CORPORATION OF OHIO.

SIDE WINDSHIELD FOR AUTOMOBILES.

Application filed November 2, 1922. Serial No. 598,465.

To all whom it may concern:

Be it known that I, FRANK H. FISSE, a citizen of the United States, residing at Cincinnati, in the county of Hamilton and 5 State of Ohio, have invented certain new and useful Improvements in Side Windshields for Automobiles, of which the following is a specification.

My invention relates to side windshields 10 for deflecting the wind, rain, dust and the like at the sides of the main windshields of automobiles, and has for its object the provision of novel means for mounting the frangible plate of the side windshield; and, 15 further, the provision of novel clamping means for clamping the frangible plate.

It is the object of my invention, further, to provide novel clamping means for the frangible plate, comprising strengthening 20 members extending along both faces of said frangible plate; and, further, to provide novel means whereby uneven strains transverse to the plane of the frangible plate are obviated or minimized; and the invention 25 will be further readily understood from the following description and claims, and from the drawings, in which latter:

Fig. 1 is a perspective view of my improved device, shown applied to the side-post of the main wind-shield, the side-post and the side shield-plate being partly 30 broken away.

Fig. 2 is a plan view of the same.

Fig. 3 is a side elevation of the same, with 35 the shield-plate and its bars adjusted to show an edge-view thereof.

Fig. 4 is a vertical cross-section taken on the line 4—4 of Fig. 2.

Fig. 5 is a horizontal cross-section taken 40 on the line 5—5 of Fig. 1.

Fig. 6 is a perspective view showing the inside of the intermediate attaching clamp; and,

Fig. 7 is a perspective view showing the 45 inside of the post clamp.

The side windshield comprises a transparent shield-plate 11 of frangible material such as glass. An attaching bar 12 extends along one face of said shield-plate. Each 50 end of the attaching bar is provided with a foot 13 having an extended clamping face 14 in which there is a central hollow 15, to form said clamping face as a narrow clamping face extending over a substantial area 55 of the frangible shield-plate.

The attaching bar is shown of substantial length and is arranged to be clamped at suitable points along its length by a clamp 16. The shield-plate is preferably pivoted by permitting rotation of the attaching bar in 60 the clamp 16. Provision is thereby made for longitudinal adjustment and for pivotal adjustment of the shield-plate.

A clamp 17 coacts with the clamp 16 for securing the shield-plate with relation to a 65 suitable support, exemplified as a post 18 of a main windshield. The connection between the clamps 17 and 16 is a pivotal connection. The connection between the clamp 17 and the post of the main windshield is 70 preferably adjustable so as to clamp upon the post at any desired height, to permit the clamp 17 to extend in suitable direction from the main windshield, and to clamp 75 posts of different thicknesses and cross-sectional forms.

In the present exemplification the clamp 17 comprises a jaw 21 and a jaw 22. The jaw 21 is provided with lugs 23, 24, between which a pivot-stem 25 extends, said pivot-stem being spaced from the body 26 of said jaw. The pivot-stem comprises sections 27, 28, which are polygonal in cross-section and separated by a reduced portion 29 of said 80 stem.

The ends of the stem terminate in frusto-conical sector-portions 31 of a fulcrum between the jaws 21, 22, the jaw 22 being provided with lugs 33, 34, provided with frusto-conical sector-recesses 35, in which the 90 frusto-conical sector-portions 31 are received for pivoting the jaw 22 on the jaw 21. Screws 36 are received through comparatively large holes in the jaw 21 and are threaded into threaded holes 38 in the jaw 95 22, for connecting the jaws 21, 22, permitting wide range of separation between said jaws, and providing pivotal connection and clamping means between said jaws.

The clamp 16 comprises the plates 41, 42. 100 The plates are provided with jaws 43, 44, at one end, and with jaws 45, 46, at their other end. A bolt 47 has a head 48, adjacent to which the shank of the bolt has a square portion 49, received in a similarly 105 shaped hole 50 in one of the plates. A nut 51 is threaded to the threaded shank of the bolt for clamping the plates toward each other.

The inner faces of the jaws 43, 44, are pro- 110

vided with ribs 54, extending lengthwise of the jaws, for cooperating with the portions of polygonal cross-section of the stem 25. The polygonal faces and the ribs are numerous about the axis of the stem so that coaction may take place between them in a great number of different positions of the jaws about the stem, to provide a great variety of different positions for the clamp 16 about said stem, and to provide for a secure positioning of said clamp with little exertion of power in clamping the clamp.

The inner faces of the jaws 45, 46, are curved on arcs of greater curvature than the curvature of the periphery of the attaching bar 12, to form separated lines of contact 55 with said bar, separated by spaces 56, the plates 41, 42, being separated by a space 57, to provide for firm clamping action of said jaws upon the bar by the exertion of comparatively little power at the clamping nut 51.

A reinforced bar 61 extends along the face of the frangible plate opposite the attaching bar 12. The reinforce bar is provided with a foot 62 at each of its ends. This foot has an extended clamping face 63, in which there is a central hollow 64, the clamping face being comparatively narrow.

The feet 13 and 62 are opposed to each other at opposite sides of the shield-plate, tension member being provided between the respective ends of the bars for clamping the shield-plate between the bars.

The clamping faces are shown as narrow opposed clamping faces distanced from and surrounding the attaching bolts, so that the clamping action upon the frangible shield-plate shall extend over a substantial area thereof but not be of substantial width, so as to avoid uneven transverse stresses upon the shield-plate.

The frangible shield-plate is in my invention reinforced at each of its sides, and uneven stresses and strains on the frangible shield-plate transverse to the frangible shield-plate or torsional with relation thereto are avoided or minimized, these stresses and strains being received and resisted by said bars and transferred from one side of said frangible shield-plate to the other side thereof through said tension members, thus relieving said frangible shield-plate from these stresses and strains.

The tension members are shown as bolts 66 shown received through holes 67 in the ends of the bar 61, and through holes 68 in the frangible shield-plate, the said bolts being threaded into threaded holes 69 in the ends of the bar 12.

Cushion washers 71, 72, which may be of soft rubber, are located between the feet of the respective bars and the glass plate, and a cushion sleeve 73, for instance of soft rubber, is received about each bolt and in the

hole of the glass plate through which the bolt passes. Effective cushioning means are thereby provided between the bars and said frangible shield-plate, preventing chipping and fracture of the glass.

The bars are spaced from the frangible shield-plate by spaces 75, 76, between the ends of said respective bars, and the bars and their connecting tension members which extend through the glass plate form a rigid frame at both sides of the glass plate and extending through the glass plate, to receive the strains and relieve the glass plate therefrom.

The bars, their feet and tension members are located within the area of the shield-plate and are spaced from all margins of said shield-plate, and the device presents a neat and strong appearance and a substantial and strong structure which is extremely durable, and prevents vibration of the glass plate.

Having thus fully described my invention, what I claim as new, and desire to secure by Letters Patent, is:

1. In a side windshield for an automobile, the combination of a frangible shield-plate, a bar extending along each face of said frangible shield-plate within the area of said frangible shield-plate, and tension members received through said frangible shield-plate having connections with both said bars for clamping said bars and said frangible shield-plate together.

2. In a side windshield, the combination of a frangible shield-plate, an attaching bar extending along one face of said shield-plate, a reinforce bar extending along the opposite face of said shield-plate, and a tension member at each end of said bars, said shield-plate provided with holes through which said tension members extend, and said tension members clamping said shield-plate between said bars.

3. In a side windshield, the combination of a frangible shield-plate, an attaching bar extending along one face of said shield-plate, a reinforce bar extending along the opposite face of said shield-plate, said bars each provided with a foot at each end thereof to space said bars from said frangible shield-plate, and tension members between the respective ends of said bars for clamping said frangible shield-plate between said feet.

4. In a side windshield, the combination of a frangible shield-plate, an attaching bar extending along one face of said shield-plate, a reinforce bar extending along the opposite face of said shield-plate, each of said bars provided at each end thereof with a foot, the feet at the respective ends of said bars being opposite each other at opposite sides of said frangible shield-plate and spaced from all margins of said frangible shield-plate, and tension members between the respective ends

of said bars extending through said frangible shield-plate for clamping said frangible shield-plate between said feet.

5. In a side windshield, the combination of
5 a fragile shield-plate, an attaching bar ex-
tending along one face of said shield-plate, a
reinforce bar extending along the opposite
face of said shield-plate, said bars located
10 within the area of said frangible shield-plate
said shield-plate provided with holes dis-
tanced from all its margins, and tension
members located in said holes and having
connection with the respective ends of said
15 bars for clamping said frangible shield-plate
between said bars.

6. In a side windshield, the combination of
a frangible shield-plate, an attaching bar ex-
tending along one face of said frangible
shield-plate, a clamp arranged to be clamped
20 to a main windshield part, a stem on said
clamp, said stem of polygonal cross-section,
a second clamp between said stem and said
attaching bar, said second-named clamp pro-
vided with jaws having a ribbed inner sur-
25 face coating with said stem of polygonal
cross-section and with jaws each having sepa-
rated lines of contact with said attaching bar
and spaced from said attaching bar between
said lines of contact, and a reinforce bar
30 extending along the opposite face of said
frangible shield-plate and having connection
with said attaching bar.

7. In a side windshield, the combination of
35 a frangible shield-plate, an attaching bar ex-
tending along one face of said frangible
shield-plate, a clamp arranged to be clamped
to a main windshield part, a stem on said
clamp, said stem of polygonal cross-section, a
40 second clamp between said stem and said at-
taching bar, said second-named clamp pro-
vided with jaws having a ribbed inner surface
coating with said stem of polygonal cross-
section and with jaws each having separated
45 lines of contact with said attaching bar and
spaced from said attaching bar between said

lines of contact, a reinforce bar extending
along the opposite face of said frangible
shield-plate, cushioning means between said
respective bars and said frangible shield-
50 plate, and connections extending through
said frangible shield-plate connecting said
reinforce bar with said attaching bar.

8. In a side windshield, the combination of
a frangible shield-plate, an attaching bracket,
55 at attaching bar extending along one face of
said frangible shield-plate, a clamp arranged
to be clamped to a main windshield part, a
stem on said clamp, said stem provided with
separated sections, each of said sections of
60 polygonal cross-section, and a second clamp
between said stem and said attaching bar,
said second clamp provided with jaws hav-
ing a ribbed inner surface coacting with said
polygonal sections of said stem and with
65 jaws arranged to be clamped about said at-
taching bar, and said attaching bar having
pivotal and axial adjustment between said
last-named jaws.

9. In a side windshield, the combination of
a frangible shield-plate, a bracket, an at-
taching bar having connection with said
70 bracket for pivotal and axial adjustment of
said frangible shield-plate, a reinforce bar
extending along the opposite face of said
frangible shield-plate, said frangible shield-
75 plate provided with holes, and tension mem-
bers connecting said bars at the respective
ends of said bars, said tension members lo-
cated in said holes, and said attaching bar,
said reinforce bar, said holes and said ten-
80 sion members located within the area of said
frangible shield-plate and distanced from all
margins thereof.

In testimony whereof, I have hereunto
signed my name in the presence of two sub-
scribing witnesses.

FRANK H. FISSE.
